ABSTRACT

A method and apparatus for mixing non-flowable solid materials disposed stripwise on a flat surface and for periodically aerating, hydrating, and shaping aerobically decomposable waste materials into a rick having compressed sides and a nearly square cross section. The apparatus includes a straddle-carrier vehicle having a tunnel means thereunder and a beater means and a scavenger means therewithin. Revolving paddles liftingly scoop clumps of waste material from one end of the rick and sling portions thereof upwardly against a forwardly and downwardly inclined front deflecting surface as an auxiliary fragmentation means and other portions upwardly and rearwardly against a rearwardly and downwardly inclined rear baffle surface from which the material is reflected downwardly between shaping compressors at the discharge end thereof to form an aerated rick which is leveled by the baffle surface.

**VEHICULAR COMPOSTING MACHINE AND
METHOD FOR AEROBICALLY DECOMPOSING
WASTE MATERIALS**

BACKGROUND OF THE INVENTION

1. Field of the Invention

This invention relates to the production of compost by the aerobic decomposition of waste materials such as agricultural wastes, animal manure and by-products, municipal and restaurant garbage, sewage products, leaves, and like decomposable waste materials. It particularly relates to an apparatus and method for providing periodic aeration, hydration, and shaping of aerobically decomposable waste materials whereby a useful compost is inexpensively formed.

2. Review of the Prior Art

It is widely recognized that the ecology of technologically advanced countries is being threatened by a number of practices for which inexpensive solutions have not yet been found. One such practice involves the disposition of solid wastes by burning, ocean dumping, and landfill.

Ecologically significant results thereof include progressive mining of top soils, by consumption of humus and trace elements through repeated applications of mineral fertilizers and production of crops in high yields, contamination of the oceans, and pollution of air in the vicinity of large cities. Landfill, a presently preferred method, requires large amounts of land which is becoming ever scarcer. Trends toward use of throw-away personal clothing, hospital gowns and bed sheets, motel bed sheets, etc., can be expected to aggravate this situation.

If an inexpensive method and apparatus can be made available for aerobically converting agricultural wastes, such as corn cobs, wheat straw, bagasse, and manure, forestry wastes, such as sawdust, bark, and wood particles, municipal wastes, such as municipal garbage and restaurant garbage, and industrial waste, such as wood-pulp by-products and food processing waste, into useful composts, ecology benefits can be two-fold: by improving soils and by reducing air, water, and land pollution. Such a method and apparatus are not available for large-scale use in converting aerobically decomposable waste materials into composts.

Compost is a dark, humus-type material which is useful as a fertilizer, as top soil, and as a mushroom growing medium at its intermediate stage. It may be formed by aerobic decomposition of waste materials with substantially no other emitted odors than those of a moist forest floor. During natural aerobic decomposition, a period of several months is required when the waste material, containing sufficient nitrogenous materials for the micro-organisms, is merely heaped in piles for decomposition thereof. In order to attain an economically practicable decomposition rate, it is consequently well recognized that the waste material must be maintained in a moist condition and must be at least periodically aerated. Aeration may be considered to be a solid-air mixing operation.

When a compost has been completely decomposed, it is often also desirable to balance its high humus content with clay and sand, as by mixing together the compost and a selected preparation of a clay subsoil and sand for manufacture of a loam. It may also be desirable to add selected quantities of minerals containing chemical elements that are to be available in major or

in trace amounts within the prepared top soil. Such minerals may be added in liquid form or as finely divided soils. Mixing of solids on a large scale may also be required, for example, in processing operations where aging and large-scale storage are involved. However, handling and mixing of one or more nonflowable solids is a difficult, slow, and energy-consuming operation that requires high capital investment with presently available methods and apparatus.

As an example of prior attempts to mix non-flowable solid materials, U.S. Pat. No. 2,994,591 of Toto describes a vehicular composting machine which is adapted to moving piles of manure to a beater for conditioning thereof in preparation of mushroom composts.

U.S. Pat. No. 3,369,797 of Cobey discloses a straddle-frame compost-turning vehicle having a longitudinally extending passageway therethrough in its direction of travel and a transversely disposed, rotating drum having helically disposed teeth projecting outwardly therefrom. The teeth have angularly inclined throwing surfaces. Vertically disposed, hydraulically adjustable retaining wings in transversely spaced relationship define the feed and discharge throats of the passageway. The machine acts upon a mass of raw material, such as raw manure deposited in a row, by straddling it, slicing into it with the projecting teeth, and throwing fragments upwardly and rearwardly to form a uniform windrow therebehin. The width of the windrows may be decreased, as composting proceeds, by adjusting the discharge wings. The windrow, however, tends to be low in height, the teeth require frequent replacement, and the raw material is chopped too finely for good aeration.

U.S. Pat. No. 3,565,585 of Engeler discloses a vehicular composting machine which comprises an inclined conveyor for picking up the compost, a conduit for spraying water onto the compost through nozzles, a stripping roller having flexible teeth, and another roller having similar teeth through which air is directed into the compost.

SUMMARY OF THE INVENTION

It is, accordingly, an object of this invention to provide a method and apparatus for mixing of non-flowable solids disposed stripwise upon a flat surface.

It is also an object to provide an aerobical decomposition method that is suitable for large-scale production of compost from waste materials and an apparatus therefor.

It is another object to provide a method and apparatus for periodically moving through a compact strip-type rick of aerobically decomposable waste materials with aeration, fragmentation, hydration, and shaping operations, whereby aerobic decomposition is maintained until a selected compost is obtained.

It is an additional object to provide a method and apparatus for liftingly detaching clumps of aerobically decomposable waste materials from an endwise wall of a compact rick thereof, fragmenting these clumps, hydrating the product thereof, and re-forming an aerated, hydrated rick with compressed sides, a flat top and nearly square cross-section therebehind.

DESCRIPTION OF THE INVENTION

In satisfaction of these objects and in accordance with this invention, the mixing method of this invention

for nonflowable solids disposed stripwise on a flat surface comprises:

- A. liftingly removing solids from an upstanding endwise wall thereof,
- B. revolving the solids upwardly and rearwardly,
- C. slingng the revolved solids rearwardly,
- D. downwardly reflecting at least a part of the slung solids between upwardly and rearwardly converging side compressing surfaces to form an aerated rick therebetween, and
- E. leveling the top of the aerated rick.

For non-flowable solid material having a propensity to form clumps and disposed stepwise on a flat surface, the mixing method of the invention comprises:

- A. forwardly and upwardly revolving a scoop means into an upstanding endwise wall of the solid material;

- B. detaching clumps therefrom with the scoop means;

- C. breaking each oversize clump, by inertial forces generated therewithin, into a scoop portion and a projecting portion;

- D. slingng the projecting portions against a forwardly and downwardly inclined front deflecting surface;

- E. classifying the projecting portions by rearwardly rebounding for a distance varying in inverse proportion to size thereof;

- F. rearwardly slingng the heavier and denser scoop portions and any rebounding projecting portions which are intercepted by said scoop means beneath a ceiling surface and toward and between a shaping means having a rearwardly and downwardly inclined baffle surface which is disposed between rearwardly and upwardly converging side compressing surfaces;

- G. slingng the lighter and bulkier scoop and intercepted projecting portions rearwardly and downwardly upon the flat surface to form the bottom part of an aerated rick;

- H. downwardly reflecting the heavier and denser portions contacting the baffle surface onto the top of the bottom part of the aerated rick to form the upper part thereof; and

- I. levelling the top of the aerated rick.

Projecting portions from the largest oversize clumps are apparently slung farther forwardly, probably because the portion of a large clump that projects beyond the scoop means, having no support for its rapidly increasing inertial forces, prematurely breaks off from the portion which is supported by the scoop means and moves tangentially with respect to the path of revolution of the scoop means, from the point of such break-off according to elementary laws of physics. The larger the projecting portion, the earlier the break-off seems to occur, so that the very large projecting portions are thrown so far forwardly that they rebound toward the endwise wall of the solid material or onto the top thereof, to be acted upon again by the advancing scoop means, whereby classification occurs.

More specifically, this aeration, hydration, and shaping method for composting waste material comprises the formation of an elongated, compacted strip of the waste material upon a flat surface, revolvingly moving a scoop means forwardly toward one endwise wall of the compacted strip and upwardly from the flat surface while inwardly compressing the sides of the compacted strip, liftingly tearing into the endwise wall to disengage a plurality of clumps therefrom, breaking off projecting

portions from oversize clumps, forwardly and upwardly slingng the projecting portions and classifying them during rebound from a front deflecting surface, hydrating and rearwardly slingng material held or intercepted

5 by the scoop means onto a hard rear baffle surface against which the clumps are disintegrated and from which the waste material is reflected onto the flat surface to form an aerated strip, and leveling the top surface of the aerated strip while exerting shaping pressure

10 upon the sides thereof to obtain a rick having a nearly square cross section and compacted sides. This method does not shave the endwise wall but instead tears out clumps and thereby maintains straw length generally equaling the dimension of the scoop means whereby

15 the aerated rick is maintained in highly bulked condition, and the finished mushroom compost retains sufficient straw or hay stems of selected length that it has adequate permeability to air during the mycelium growth stage.

20 This operation is repeated every three days during normal weather upon each compacted rick. Winter temperatures as low as -20° F. merely extend the heating period for one to two days. Steam heating of the underlying support surface may then be practicable if a production schedule must be maintained.

25 For mushroom cultivation, the compost should be available at an intermediate stage when the compost has sufficient bulk to retain moisture and air that the mycelium needs for feeding on killed bacteria. For 30 other agricultural uses and for forming topsoil, however, the compost should be completely decomposed and should be turned about six times instead of three times as is needed for mushroom composts.

35 A rick is herein defined as an elongated strip made of aerobically decomposable material and having slightly tapered and compressed sides and a flat top. Typical rick measurements, before decomposition begins, are a bottom width of 6 feet, a top width of 7 feet, a length of 300 feet, and an initial height of 7 to 9 feet. 40 Shrinkage in height during the halfway decomposition for optimum formation of mushroom compost is generally about 30-40 percent. The moisture content of this mushroom compost is about 65-80 percent.

45 Composts for mushroom cultivation are presently made from a mixture of ground corn cobs and alfalfa and a relatively small amount of chicken manure. Initial bulk density data for ground corn cobs is about 340-360 air-dry pounds per cubic yard, the material being at about 15 percent moisture content. Initial bulk density for ground alfalfa is about 100-150 air-dry pounds per cubic yard. Hammer-milled garbage is believed to have an average dry density similar to that of corn cobs. Nitrogen content should be 1.5 percent dry basis.

55 The vehicular composting machine of this invention continuously advances through and ingests a compacted rick with a clump scooping means, a clump disintegration means, a nitration and hydration means, and a rick reforming means, whereby the machine continuously displaces the entire compacted rick and continuously rebuilds therebehind an aerated, fragmented, and selectively nitrated and hydrated rick. This machine comprises a straddle carrier vehicle of known construction having a frame and a power supply means, a tunnel means which is straddled by and attached to the vehicle, a rick intake means which is disposed at the front end of the vehicle, a beater means having the

scoop means projecting outwardly therefrom, a scavenger means, a hydrating means if necessary, and a rick shaping means at the discharge end of the vehicle. The beater means is disposed transversely to and approximately midway of the longitudinal axis of the vehicle and within the tunnel means so that the vehicle is divided into an intake section and a discharge section. The beater means is rotatably supported by the vehicle and is operatively connected to the power supply means.

The tunnel means comprises a horizontally disposed ceiling which is rigidly attached to the frame, a pair of vertically disposed tunnel walls which are conjoined to the ceiling and rigidly attached to the frame, and an impact deflector which is hingeably attached to the ceiling at the intake end of the vehicle. The impact deflector is hinged approximately vertically above the forwardmost edge of the beater means and is adjustably suspended by an adjustment means which permits the impact deflector to be positioned for deflecting most of the slung material, received from the scoop means, toward the upper portion of the beater means along a zone of return impact forward of the topmost edge thereof.

The rick intake means comprises a pair of laterally spaced and outwardly diverging intake side sweepers and a pair of inwardly bulging wheel wells. The intake side sweepers are attached to the tunnel walls and, in cooperation with the wheel wells, form a guiding means for the vehicle whereby the vehicle is able to follow the rick upon which it is being operated without attention by an operator. The sweepers may be rigidly or hingeably attached to the tunnel walls and preferably are hinged and hydraulically operated.

The rick shaping means comprises a pair of discharge side compressors and a discharge top baffle positioned therebetween and hingeably attached to the ceiling at the discharge end of the vehicle. The pair of discharge side compressors mutually converge upwardly and rearwardly. The pair of discharge side compressors comprises a pair of packing compressors, each being rigidly attached to one of the tunnel walls, and a pair of shaping compressors, each being hingeably attached to one of the packing compressors. The discharge top baffle reflects slung material downwardly and, if received directly from the beater means, also forwardly toward the scavenger means. Structurally, this baffle may be considered part of the tunnel means, but functionally it interacts with the packing compressors and the scavenger means to form the aerated rick.

The beater means principally comprises a rotation means and a scoop means, such as a hammermill having a scoop means attached to each hammermill arm, but preferably comprises a beater drum and a plurality of scoop means attached to, and in combination with, the surface thereof. Each scoop means has an open outer end, two outer corners, and an open side facing the direction of revolution of the beater drum. The closed side may be rounded, such as is formed by a longitudinal half-section of pipe, or may be angular, such as is formed by a longitudinal section of angle iron, to make a beater paddle. The pair of angularly attached blades of a beater paddle are disposed mutually perpendicularly and in radial alignment with the beater drum surface whereby a concavity is formed between the pair of blades and in combination with the surface of the beater drum. This concavity faces forwardly in

the direction of rotation of the drum, whereby the concavity, with its bounding structure, performs as an upwardly and forwardly revolving scoop as the drum rotates. The beater paddles are preferably disposed in longitudinal rows spaced 60° apart along the periphery of the beater drum and are preferably circumferentially disposed along approximately a 45° relationship to the longitudinal rows.

The hard edges of the beater paddles tear into the wall of waste materials at the exposed end of the compacted strip upon which the beater paddles are operating. By liftingly and forwardly tearing into this wall, clumps are disengaged therefrom. The clumps generally are larger than the concavity and are curvilinearly accelerated as the drum moves upwardly. This acceleration generally breaks an oversize clump into a scoop portion which is retained by the concavity and a projecting portion which is slung upwardly, at about a 30° forward angle, into contact with a forwardly and downwardly inclined impact deflector which rebounds the projecting portion toward the upper part of the beater drum. The scoop portion, however, is generally retained until the paddle has approximately at least reached its topmost position, whereupon the retained scoop portion has acquired enough velocity and consequently enough centrifugal force to slide outwardly beyond the paddle and be slung rearwardly toward the ceiling and/or the discharge top baffle and/or the ground or flat surface upon which the vehicle is operating. The coefficient of friction, between the scoop portion and the inner surfaces of the blades, and the mass of each scoop portion seem to be the determining factors as to its departure position along the drum periphery.

The scavenger means comprises an arcuately shaped plow having a forwardly disposed shave edge which is disposed transversely to the vehicle and in an annular relationship to the beater drum at the forefront of the discharge section of the machine. The shave edge faces toward the front end of the vehicle and is aligned with the bottom edges of the tunnel walls so that, in cooperation with the beater drum, it completely removes the last part of the compacted rick.

The scavenger means further comprises a barrier guide which is rigidly attached to the plow along the top edge thereof and is rigidly attached to the packing deflectors at its ends. The barrier guide more effectively separates the continuously forming aerated rick from the beater drum and helps to form the lower part of the sloped front wall of this aerated rick by stopping reflected material from the discharge baffle and guiding it downwardly to form this continuously advancing sloped endwise wall into which some scoop portions are slung directly. Scoop portions slung against the ceiling and then against the discharge top baffle are impacted upon this sloped endwise wall to build it to a level slightly higher than the bottom edge of the discharge top baffle.

The hydrating means comprises a front header and a rear header which are disposed transversely of the longitudinal axis of the vehicle and straddling the beater drum. These headers are connected to an extensible water supply means. Water, a chemical solution, or a trace-element slurry is sprayed therefrom through a plurality of nozzles which are selectively disposed to direct water forwardly, downwardly, and rearwardly. For mixing operations wherein aerobical decomposi-

tion is not needed, the hydrating means need not be installed in the vehicular composting machine.

The power supply means of this vehicle may be gasoline, diesel, or LP-gas powered. Engines of 120 to 200 horse power are suitable. The vehicular composting machine of this invention moves through a rick at up to 7 feet per minute, although adding a greater number of scoops and operating the beater means at higher rotational speeds significantly increases this speed. A typical speed of operation, for a machine having a minimum of scoops for optimum bulkiness of the aerated ricks formed therewith, is about 4 feet per minute. Operating speeds on a highway are typical for straddle carrier vehicles and may be up to 25 mph.

As the waste material aerobically decomposes, successive aeration-hydration-shaping operations encounter a progressively more friable material so that a clump disengaged therefrom tends to be more nearly the same size as the scoops and is slung rearwardly without breaking a projecting portion therefrom.

Consequently, it is feasible and within the scope of this invention to provide machines having diverse scoop means. One vehicular composting machine can thus be provided which is suitable for the first aeration; another vehicular composting machine can be provided having slightly different scoops which are more nearly suitable for dealing with more friable material; and a third machine can be provided having paddles which are suited for very friable material, such as paddles having larger blades or scoops with curved cutting edges. In the vehicular composting machine specialized for the first aeration, for example, scoops may be of a pitchfork type having a plurality of tines of suitable length, thickness, and curvature, depending upon the proportion of projecting and scoop fractions which are desired.

BRIEF DESCRIPTION OF THE DRAWINGS

The vehicular composting machine of this invention and the compost aerating method of this invention may be understood more clearly by referring to the drawings, as follows:

FIG. 1 is a diagrammatic side elevation of the vehicular composting machine as it is passing through a rick of compost.

FIG. 2 is a diagrammatic plan view showing the vehicular composting machine while moving between rows of composts stacked on a concrete wharf and aerating the middle row. FIG. 1 may be considered to be a cross-sectional view looking in the direction of the arrows 1-1 in FIG. 2.

FIG. 3 is a diagrammatic rear view showing the three rows of FIG. 2, looking in the direction of the arrows 3-3 in FIG. 2.

FIG. 4 is a front elevation of the machine.

FIG. 5 is a diagrammatic perspective view of the steering mechanism and front wheel assembly.

FIG. 6 is a diagrammatic perspective view of the hydraulic power means and rear wheel drive means for the machine.

FIG. 7 is a diagrammatic perspective view of the drum drive mechanism.

FIG. 8 is a right-side elevation view, looking in the direction of the arrows 8-8 in FIG. 4, with the beater means and scavenger means indicated in phantom.

FIG. 9 is a sectional elevation view showing the left side of the machine, looking in the direction of the arrows 9-9 in FIG. 4.

FIG. 10 is a sectional plan view looking in the direction of the arrows 10-10 in FIG. 8.

FIG. 11 is a sectional elevation view looking in the direction of the arrows 11-11 in FIG. 8, looking toward the rear of the machine.

FIG. 12 represents three sizes of paddles on the beater drum and typical positions for straw crossed in the concavities thereof.

FIG. 13 is a diagrammatic sectional elevation view of another embodiment of the vehicular composting machine having a tunnel means with a raised ceiling in the discharge section, a hammermill beater means, a carom deflector thereabove, a funnel compressor, and a curved safety shield which is hingeably attached to the bottom edge of the front deflector.

FIG. 14 is a perspective view of a hammermill arm and scoop used in the hammermill beater means of FIG. 13.

FIG. 15 is a fragmentary perspective view of a rounded scoop attached to a fragment of the beater drum surface.

FIG. 16 is a top view of the right tunnel wall in the discharge section of the embodiment shown in FIG. 13, which shows the funnel compressor hingeably attached thereto and the slide mounting for the shaping compressor.

FIG. 17 is a diagrammatic plan view of a multi-rick embodiment of the vehicular composting machine, which is particularly suitable for solid waste composting operations on a large scale, and a fragment of a quadri-rick formed therewith.

FIG. 18 is a sectional elevational view, looking in the direction of the arrows 18-18 in FIG. 17, which shows the discharge end of the multi-rick embodiment of FIG. 17.

DETAILED DESCRIPTION OF THE PREFERRED EMBODIMENTS

The vehicular composting machine 15 shown in the drawings comprises a straddle carrier vehicle 30 which comprises a frame 40, a power supply means 50, a pair of laterally spaced and vertically disposed front posts 33 which are rotatably attached to the frame 40, a pair of laterally spaced and vertically disposed rear posts 33 which are attached to the frame 40 and are longitudinally spaced from the front posts 33, four wheels 31, each being rotatably attached to one of the posts 33 at the bottom thereof, a wheel drive means 61 which is operatively connected to the power supply means 50, a drum drive means 51 which is also operatively connected to the power supply means 50, and a steering and control means 80.

The straddle carrier vehicle 30 is of conventional type. Its wheels 31 may be adjusted within narrow limits by a height control means comprising a rocker arm 35, a height-control knob 36, and a spring 37. The frame 40 comprises longitudinal box channels 41, cross channels 43, and post support lugs and collars 45 by means of which the wheel posts 33 are attached to the channels 41. The highly preferred height control means is fully hydraulic and comprises a hydraulic cylinder at each wheel post 33 whereby the entire machine is raised or lowered with respect to a flat supporting surface, such as the concrete wharf 19.

The power supply means 50 comprises, as clearly shown in FIGS. 6 and 7, a wheel drive means 61 and a drum drive means 51. The drum drive means 51 is taken directly from the main power unit 52 by means of sheaves 55a, 55b which are connected with a V-belt drive 56. The power is then transmitted through an overriding clutch 54, drum drive chains 58a, 58b, and sprocket wheels 59a, 59b to the drum drive socket 59c. The wheel drive means 61 comprises the hydraulic pump 62 which is connected with a power take-off to the engine 52, a hydraulic power unit 63, a 10-speed transmission 65, a drive shaft 66, a differential 67, axles 64, and sprocket wheels 68 which move wheel drive chains 69. These chains 69 are connected to the wheel sprockets 32 whereby the rear wheels 31 are driven. In the highly preferred embodiment all power transmission is hydraulic so that the drum drive means, the wheel drive means, and the steering and control means are all hydraulically driven.

The steering and control means 80, with which an operator sitting in the seat 39 steers and controls the vehicular composting machine 15, comprises a wheel reversal shift 83 and a transmission shift 85, shown in FIG. 6, and a drum control shift 81, shown in FIG. 7, which operates the clutch 53. The operator steers the vehicle with the steering wheel 87, as indicated in FIG. 5, which turns the front wheels 31 by means of the front tie rod 89.

The engine 52 may be gasoline, diesel, or LP-gas operated. The operator seat 39 is shown as being uncovered at the top of the vehicle 30, but it is preferred to place the operator in a covered cab at the front of the vehicle at a substantially lower elevation, such as at the front of the high-discharge embodiment shown in FIG. 13 with the engine alongside.

The vehicle 30 and its operative mechanisms have been described in some detail hereinbefore in order that the operation of the vehicular composting machine 15 of this invention may be clearly understood. However, the straddle carrier vehicle 30 is not a part of this invention, and it should be understood that the inventive portion of this disclosure follows hereinafter. This inventive portion comprises the tunnel means 90, the beater means 110, the scavenger means 130, the rick intake means 140, the hydrating means 150, and the rick shaping means 170. However, the invention may be more descriptively dichotomized by listing the impact deflector means 101 separately from the tunnel means 90 and the discharge baffle 191 separately from the rick shaping means 170.

The tunnel means 90 comprises the ceiling 19, the tunnel walls 93, 95, and the impact deflector 101. The ceiling 91 is horizontally disposed and is rigidly attached to the frame 40. The pair of vertically disposed tunnel walls 93, 95 are conjoined to the longitudinally disposed side edges of the ceiling 91 and rigidly attached to the frame 40. The impact deflector 101 is hingeably attached to the ceiling 91 with the impact hinge 103 which is disposed transversely of the longitudinal axis of the vehicle 30 so to provide an arcuate path of travel 104. The impact deflector 101 is suspended by the adjusting cable 105 which is stored on the reel 107 which is operated by the handle 109. Because the bottom edge of the deflector 101, as shown in FIG. 9, is within the tunnel means 90 and a short distance above the top surface 21 of a compacted rick, the machine 15 performs the valuable function of sweeping the steam

always associated with the aerobical decomposition into and through the tunnel means 90 so that the operator of the machine 15 is not bothered thereby and has uninterrupted vision. When projecting portions of oversize clumps break off from the scoop portion caught on the paddles 113 before acquiring high velocity and are deflected from the impact deflector 101 so as to fall back upon the compact rick 21, a wave-like crest 22a of loose material is created immediately ahead of the beater means, as shown in FIG. 9. Fresh air, sweeping beneath the bottom edge of the deflector 101, passes over this crest 22a and entraps the normally considerable quantity of steam which continually escapes from the sequentially and continuously exposed endwise wall in front of the beater means.

The high-discharge embodiment shown in FIG. 13 has a quadri-sectioned ceiling; the horizontally disposed front ceiling 92a upon which the operator's cab and the engine are disposed, the horizontally disposed ceiling 92b upon which the hydraulic power unit is disposed and to which the hydraulically operated deflector 101 is hingeably attached, the downwardly and forwardly inclined ceiling 92c, and the horizontally disposed rear ceiling 92d to which the hydraulically operated baffle 191 is hingeably attached. This embodiment is useful for very bulky materials. When a beater drum is used as the rotation means instead of the hammermill 210, a secondary pull-off roller (not shown in the drawings) is rotatably attached to the tunnel walls 30 in parallel to the beater drum and with its shaft at about the top of the beater drum so that pull-off teeth on the pull-off roller, revolving at a higher speed than the periphery of the beater drum, can strip waste material therefrom.

Also shown in FIG. 13 is a safety shield 230, which is hydraulically operated and hingeably attached to the bottom edge of the deflector 101 with the hinge 231, having a curved front surface 233, a curved rear surface 234, and a straight, horizontally disposed bottom edge 236. When deflector 101 is hydraulically moved to its vertical position, the shield 230 may be brought into close proximity to the beater means in its vertical position 230' whereby operating personnel can move about in front of the beater means and between the sweepers 141, 143 in complete safety.

Moreover, the safety shield is a very useful operating part of the vehicular composting machine for completely cleaning up the terminus of a compacted rick with a minimum of auxiliary labor. When this terminus, sloping away from the advancing machine, becomes lower than the shaft of the beater means, the scoops meet insufficient resistance to their forward and upward revolving motion and tend to toss material arcuately ahead so that the terminus becomes a very low and highly elongated strip ahead of the machine. By moving the shield 230 downwardly, the terminal material may be raked toward the beater means and compressed against the thrust of the scoops.

The beater means 110 comprises a rotation means such as a beater drum 111, and a hammermill 210. The beater drum 111 has a scoop means, such as the rounded scoops 112, shown in FIG. 15, and the beater paddles 113 projecting outwardly therefrom, and a central shaft 121, which is rotatably supported in bearings 123 at either end thereof. The beater drum 111 is disposed transversely to and approximately midway of the longitudinal axis of the vehicle 30 and within the

tunnel means 90 whereby the beater drum 111 divides the vehicle 30 into an intake section and a discharge section. Suitable rotation speeds for a beater drum 111 of 6-foot diameter are 80-130 rpm.

The beater paddles 113 comprise and are formed by a pair of intersecting and rigidly attached blades 114 which are preferably disposed mutually perpendicularly and in radial alignment with the beater drum 111. The blades 114 have outward blade edges 115 and form a concavity 117 with the adjacent surface of the beater drum 111. These blade edges 115 describe a periphery of travel 119 with reference to which the height control means for the wheels 31 must be carefully adjusted. Each concavity 117 faces forwardly in the direction of rotation 125 of the beater drum 111, whereby the concavity 117 forms a scoop during rotation of the beater drum 111.

For optimum retention of bulkiness, the beater paddles 113 are preferably disposed in longitudinal rows spaced 60° apart along the periphery of the beater drum 111 and are preferably circumferentially disposed along approximatel a 45° relationship to the longitudinal rows. The beater drum 111 is preferably about 6 feet in diameter but may be as small as 4 feet in diameter and as large as 9 feet in diameter for operating on settled ricks 25a having a top surface 21 which is 5 to 9 1/2 feet above a concrete wharf 19. For very bulky ricks more than 9 1/2 high, as may occur before the first aerobical decomposition, it may be desirable to install a take-off roller whose teeth take past the scoops on the drum surface, as discussed hereinbefore for the high-discharge embodiment shown in FIG. 13.

The blades 114 project outwardly from the surface of the drum 111 for a distance of 6 inches so that a 7-foot periphery 119, as indicated in FIG. 9, is described for a 6-foot diameter drum 111. At rotational speeds of 80-130 rpm, peripheral velocities of 1,800-2,900 feet per minute are attained. However, other size relationships are feasible without departing from the principles of this invention.

Moreover, the hammermill 210, as shown in FIGS. 13 and 14, having a shaft 201, arms 212, and paddles 213, is effective on a wide variety of non-flowable solids. The paddles 213 comprise a pair of angularly disposed blades 214, a concavity plate 217, 9and a deflecting plate 218. Alternatively, the blades 214 may be replaced with the rounded scoop 112, shown in FIG. 15, by rigidly attaching the rounded portion thereof to the concavity plate 217. In general, any scoop means is satisfactory which provides a tearing action upon the endwise wall of waste material at one end of a settled rick 25a, liftingly scoops a clump therefrom during movement of the machine forwardly toward the endwise wall and upwardly from the concrete wharf 19, retains the scooped-out clumps during upward and rearward curvilinear movement, and thereupon slings the clump rearwardly.

As shown in FIG. 12, a scoop may also vary in size. For beater paddles formed of a pair of angularly disposed blades 114, scoops may be classified as "fine," "medium," and "coarse," as shown in FIGS. 12a, 12b, and 12c, respectively. Clumps caught therewith are correspondingly varied in size, and the scoop portions thereof are proportionate as the sharp side edges 116 tear into the endwise wall of a rick. Of even greater significance for bulk retention is the effect of scoop size upon straw length for mushroom usage. As a general

relationship, the straws 71,73,75 tend to be somewhat longer than the width of a blade 114 but vary directly therewith. Widths of 6 inches for the blades 114 have been used on a wide variety of solid materials and are considered to correspond to the medium classification of FIG. 12b.

At the front end of the straddle carrier vehicle 30 is a rick intake means 140 which comprises a pair of laterally spaced and outwardly diverging intake side sweepers 141,142 and a pair of inwardly bulging wheel wells 143,148. The left-side sweeper 141 and the right-side sweeper 142 are rigidly attached to the front edges 96 of the left tunnel wall 93 and right tunnel 95, respectively, and are each strengthened by the supporting brackets 147. The left wheel well 143 and the right wheel well 148 are rigidly attached to and effectively replace the left tunnel wall 93 and the right tunnel wall 965, respectively, having tapered edges 149 which aid in the intake of a settled rick 25a. Because the wheel wells 143,148 bulge inwardly into the tunnel formed by the tunnel sides 93,95, as clearly indicated in FIGS. 4 and 10, they provide a delayed compressive action to the incoming compost and prevent the compost from becoming wedged into the corners formed by the tunnel walls 93,95, the concrete wharf 19, and the surface of the beater drum 111. In addition, the wheel wells 143,148 augment the steering effect of the side sweepers 141,142. However, the machine 15 is perable with the sweepers 141,142 as the sole intake means, particularly if they are hydraulically actuated.

The forward edges 144 of the side sweepers 141,142 must be completely outward of a settled rick 25a, as indicated in FIG. 2, and must completely cover the wheels 31, as indicated in FIG. 4. The top edges 145 of the side sweepers 141,142 must also be slightly above the top surface 21 of a settled rick 25a, as indicated in FIG. 1. In order to sweep up scattered side material, each sweeper 141,142 may be provided with a mold-board plow, a rotatably upright roller, an upwardly moving conveyor, or like means for sweeping up this scattered material and moving it to the top of the compacted ricks.

The scavenger means 130 comprises a plow 131 and the barrier guide 137, although the vehicular composting machine 15 may be operated successfully without the barrier guide 137, particularly on sticky materials. The ends 134 of the plow 131 and the ends 138 of the barrier guide 137 are rigidly attached, as shown in FIG. 9, to the tunnel walls 93,95 and to the packing compressors 171,173, respectively, as set forth hereinafter. The plow and the guide 137 are supported by a plurality of braces 132.

The plow 131 has a shave edge 133 at its bottom and a top edge 135 with which the top of the barrier guide 137 is conjoined. The plow 131 is substantially arcuate and is annularly spaced from the beater drum 111, as shown clearly in FIG. 9, slightly beyond the periphery of travel 119 of the blade edges 115. The shave edge 133 thus acts in cooperation with the plow 131 as does the cutting edge of a turnplow, so that all material which protrudes upwardly beyond the bottom edges 98 of the tunnel walls 93,95 is caught by the shave edge 133 and exposed to the revolving paddles 113 so that the plow 131 and the beater drum 111 thus cooperate in attacking and completely removing the endwise wall of waste material of a settled rick 25a as the machine 15 moves continuously and sequentially through it.

The hydrating means 150 comprises the front header 151, the rear header 153, a pair of longitudinal headers 155, a pair of intake lines 164, a pair of intake valves 163, and a pair of intake connections 165 to extensible hoses which are not shown in the drawings and which pass over the pair of hose guides 167. Each header 151,153 is provided with a plurality of nozzles. These nozzles are the forwardly directed nozzles 157, the vertically directed nozzles 159, and the rearwardly directed nozzles 161. As shown in FIGS. 9 and 10, these nozzles are disposed along the length of each header 151,153. The water sprayed therefrom, at a pressure of 60-200 psig as forward discharge sprays 156, downward discharge sprays 158, and rearward discharge sprays 162, vigorously wets the agitated waste material therebeneath.

The rick shaping means 170 comprises a pair of discharge side compressors and a discharge top baffle 191. The pair of discharge side compressors mutually converge upward and rearwardly. Each discharge side compressor comprises a packing compressor and a shaping compressor. The left packing compressor 171 is rigidly attached to the left tunnel wall 93 by means of a beveled connecting surface 175, and the right packing compressor 173 is similarly attached to the right tunnel 95 with a beveled connecting surface 175. Each packing compressor 171,173 is rigidly attached to its respective tunnel wall 93,95 along its bottom edge to the point that the bottom edge of the barrier guide 37 conjoins therewith, as shown in FIG. 10. The top edge of each packaging compressor 171,173 is rigidly attached along its entire length to the ceiling 91. The ends 134 of the plow 131 and the ends 138 of the barrier guide 137 are each rigidly attached, as by welding, to the packing compressors 171,173 and tunnel walls 93,95, as shown in FIG. 10.

The left shaping compressor 177 is hingeably attached by three hinges 181 to the rear edge 172 of the left packing compressor 171, and the right shaping compressor 179 is similarly attached by three hinges 181 and positioning arms and brackets 182 to the rear edge 174 of the right packing compressor 173. Each shaping compressor 177,179 has a top edge 183, a rear edge 185, a bottom edge 187, and an inclined edge 189. The inclined edges 189 help to compress and shape the sides 27 of a freshly turned rick 25b, as indicated in FIGS. 2 and 3.

The discharge top baffle 191 has a hinge 193, by which it is attached to the vehicle 30, and a bottom edge 194. The discharge top baffle 191 is positionally adjusted by means of a suspending cable 195 which is stored on a reel 197 and controlled by a handle 199 so that its bottom edge 194 moves through a periphery of travel 196. As shown in FIG. 9, its bottom edge 194 is specifically adjusted so that it levels the top surface 23' of the outgoing aerated rick 25b, thereby creating a leveling wave 22b, to the desired height 23 prior to emergence of the rick 25b from sidewise packing between the shaping compressors 177,179.

As indicated in FIGS. 13 and 17, a pair of hydraulically operated funnel compressors 200 may also be used as an auxiliary and selectively operable side packing means. Each funnel compressor 200 is hingeably attached to the inner surface of one of the packing compressors 171,173 along a vertically disposed hinge and is hydraulically movable with respect thereto. By this means, and alongside the aerated rick as it is build-

ing within the tunnel means 90, the sides 27 of the aerated rick can be selectively compressed and the top 23 can be built to any reasonable height.

As shown diagrammatically in FIG. 16, the hydraulically operated shaping compressor 179 is hingeably attached to the right packing compressor 173 with a hydraulic slide mounting 184, whereby it can be slideably aligned with the trailing edge of its associated funnel compressor 200. The hydraulic cylinder 186, for operating the shaping compressor 179 and pressing it against the right side 27 of an aerated rick, is mounted with a resiliency-imparting means. With both shaping compressors 177, 179 resiliently and hydraulically operated and slideably alignable with a pair of funnel compressors 200, the vehicular composting machine 15 is able to shape a very wide range of nonflowable solid materials into ricks of selected height and width.

For aerobically decomposing solid wastes, such as municipal garbage, the multi-rick embodiment shown in FIGS. 17 and 18 is particularly useful because of its large size. The multirick machine comprises a plurality of discharge top bafflers 251a,b,c,d, which are hingeably attached to a ceiling 91, and a plurality of vertical separators 241,242,243, which are rigidly attached to the ceiling 91 and suitably braced. Each separator 241,242,243 has a relatively blunt leading edge 245 and a midsection of uniform thickness from top to bottom that tapers rearwardly very gradually toward a trailing edge 247. When this machine moves through a quadri-rick disposed on a flat surface 19, it forms two outer ricks 253a, 253d, having one tapered side 254,255, respectively, and one or more inner ricks, such as the ricks 253b,253c, having straight sides bordering on breathing slots 257 by means of which the quadri-rick maintains its aerobic condition, wherein air tends to enter a rick and exhaust through or near its top.

DESCRIPTION OF THE PREFERRED METHOD

Typically, a flat area is selected, preferably a hard-surfaced area such as a concrete wharf 19 shown in FIGS. 1-3. A plurality of truckloads of aerobically decomposable material are deposited contiguously, along approximately straight lines, to form a plurality of parallel strips 24,25,26 having a length of about 300 feet. If no pre-blended, separate materials may be deposited alternatively or as superposed strips to be mixed by the machine 15. From each strip, samples are taken at intervals, blended, split, etc., and analyses are made for moisture content and nitrogen content. The average amounts of water and a nitrogenous material, such as ammonia, calcium cyanamide, cotton seed meal, chicken manure, urea, and ammonium nitrate, to be added are then calculated so that an initial nitrogen content of 1.5 percent, dry basis, is obtained.

The machine 15 is brought to the end of the first strip 24 of the strips 24,25,26, with its intake means 140 disposed to sweep all material into its tunnel means 90. With water intake valves 163 and nitrogen supply means adjusted, the machine 15 is moved through the first strip 24 from end-to-end while moving in direction 29a and is then turned 180° so that it can advance upon the next strip 25 while moving in direction 29b, finally moving in direction 29c through the rick 26. In similar fashion, the machine 15 moves through all of the piled material, converting linearly contiguous piles into

shaped ricks 24,25,26 having a moisture content of 70 percent and a nitrogen content of 1.5 percent.

After about three days, when the temperature inside the ricks 24,25,26 has climbed to 140°-183° F. and the tops thereof, such as the top 21 of the settled rick 25a, have noticeably settled about 1 foot, the machine is moved through the compact ricks, foot-by-foot, to change each compact rick into an aerated rick, such as the compact portion 25a becoming the aerated portion 25b of the rick 25, as shown in FIGS. 1-3.

The discharged aerated ricks 24 and 25b have a top 23 that is usually 6 inches to 1 foot higher and a cross-section that is more nearly square than that of the settled compact rick 26, as is apparent in FIG. 3, with tightly packed sides 27, as compared to the loose sides 28 of the compact or settled rick 26. The higher top 23, however, generally settles in one day to the height of the compacted top 21.

In operating the machine of this invention on municipal, restaurant, and hospital wastes, it is practical to combine sewerage treatment facilities with the composting operation by using sewerage effluent as the feed water to the hydrating means 150 and by adding sewerage sludge, as nitrogenous-bearing material, to the initial waste material. Because the temperature within the ricks 24,25,26 rises as high as 180° F or even higher, any harmful organisms that are added are largely killed. By this combination, aqueous pollution loads from phosphate-bearing sewerage effluents are obviated, and the phosphates are used directly for soil enrichment.

The method of this invention may be more clearly understood by reference to the following examples in which a vehicular composting machine constructed according to FIGS. 4-11 was used.

EXAMPLE I

Using front-end loaders, a strip 300 feet long of mixed timothy hay and orchard grass was laid on a concrete wharf and approximately an equal amount by weight, dry basis, of crushed corn cobs was added thereto. Sufficient dry chicken manure was added at intervals by the foreman according to his experience and judgment to obtain 1.5 percent nitrogen by weight, dry basis.

The vehicular composting machine 15 moved through this pile slowly while adding water freely, the foreman adjusting the valves 163 as he walked alongside and periodically felt the wet, shaped rick with his hand. The rick has shaped flat on top, and nearly 8 feet high. The next day, although the outside temperature was not far above freezing, the temperature at 18-inch depths within the rick had reached about 135° F. The temperature then dropped the next day and rose again on the third day when steam could be seen seeping from the sides of the rick about 1 foot to 2 feet below its top. Three days of such aerobic activity caused the aerated rick to become a compacted rick about 7 feet high.

The machine 15 then moved again through the compacted rick while adding more water with its hydrating means 150. Steam blow out copiously between the sides of the baffle 191 and the shaping compressors 177,179. The newly aerated rick had a height of 7 1/2 feet.

This operation was repeated once more to produce a mushroom compost after the succeeding and final loading operation.

EXAMPLE II

A 90-foot strip of municipal garbage from Wilmington, Delaware, had been machine picked and then quickly hand picked, allowed to decompose for 3-4 months while being turned about three times, mixed with a small proportion of fresh, shredded waste paper, and formed into a strip with another machine. This strip was straddled by the machine 15. Without adding water, the rick was reformed into a low rick, about 8 feet wide at its bottom and 4 1/2 feet high, by the machine 15 at about 5 feet per minute. The material was slightly warm to the touch, although the weather was cold.

Visual inspection of the finished aerated rick showed a truck innertube, a bicycle innertube, short sticks, small stones, many aluminum cans, a great deal of rigid and sheet plastic, much undercomposed paper, and a large amount of gray, earthy-appearing compost. Inspection of the tunnel means 90 revealed that the top edge 135 of the scavenger means 130 was festooned with a solid mass of draped polyethylene.

EXAMPLE III

A 200-foot long pile of mushroom compost tail ends which had been turned about six times and thoroughly decomposed so that it was mucky, black, and showing no sign of hay or straw, was straddled by the machine 15. The aerated rick had 65-70 percent moisture and after shaping had slick sides. However, decomposition was substantially completed, and no appreciable amount of steam was produced. No water was added while mixing the rick.

Inspection of the discharge section of the machine, after it had completely moved through the rick, showed that the polyethylene plastic remained on the top edge 135 and was partly covered with black, sticky compost.

EXAMPLE IV

Truck loads of fresh stockyard cow manure were laid on a concrete surface in a strip about 60 feet long. The machine 15 straddled the strip shortly after completing the previous experiment and moved through it without adding water, because the cow manure was sufficiently moist, at 4.5 feet per minute, producing a low demonstration rick that was five feet high.

The temperature of the manure was 91° F. as probed with a steel-encased dial thermometer to a depth of about 18 inches. A slight quantity of steam arose. Midway through the rick, the machine 15 stopped and backed up with the beater drum 111 still rotating. It was able to move backwards about 1 foot, the distance typically available in a hay-corn co rick.

Thereafter, the machine, after resuming its mixing operation, ran without an operator on board for about 30 feet and reached the end of the rick. It was noticeable that the sticky cow manure would not form a smooth top when levelled by the bottom edge 194 but agglomerated into rough chunks about 8-12 inches across having deep clefts therebetween, a condition conducive to effective breathing of the rick during its aerobic decomposition.

The top edge 135 of the scavenger means 130 retained the polyethylene plastic, and a quantity of cow manure had displaced the compost and was wedged thereabove and touching the periphery of the beater drum 111.

It will be readily apparent to those skilled in the art that various modifications and alterations may be made in the aeration method described hereinbefore and in the form, construction, and arrangement of the various parts of the vehicular composting machine without departing from the basic principles and purpose of the invention. Such modifications and alterations are consequently intended to be included within the spirit and scope of the invention unless necessarily excluded therefrom by the appended claims when broadly construed.

What I claim is:

1. A vehicular mixing machine, for continuously and sequentially mixing non-flowable solid materials disposed strip-wise on a flat surface comprising:

- A. a straddle carrier vehicle having a frame and a power supply means;
- B. a tunnel means which is straddled by and attached to said vehicle;
- C. a rick intake means which is disposed at the front end of said vehicle;
- D. a beater means, having a plurality of scoop means projecting outwardly therefrom, which:
  - 1. is disposed transversely to and approximately midway of the longitudinal axis of said vehicle and within said tunnel means whereby said vehicle is divided into an intake section and a discharge section,
  - 2. is rotatably supported by said vehicle, and
  - 3. is operatively connected to said power supply means;
- E. a scavenger means which is disposed parallel and closely adjacent to said beater means and in the forefront of said discharge section; and
- F. a rick shaping means.

2. The vehicular mixing machine of claim 1 wherein said tunnel means comprises:

- A. a horizontally disposed ceiling, which is disposed above said beater means and is rigidly attached to said frame,
- B. a pair of vertically disposed tunnel walls which are conjoined to said ceiling and rigidly attached to said frame, and
- C. an impact deflector which is hingeably attached to said ceiling.

3. The vehicular mixing machine of claim 2 wherein the impact hinge attaching said impact deflector to said ceiling is disposed transversely to said longitudinal axis and is aligned approximately vertically above the forwardmost edge of said beater means.

4. The vehicular mixing machine of claim 3 wherein said impact deflector is adjustably suspended from said impact hinge by an impact adjustment means which permits said impact deflector to be positioned for reflecting slung material, received from said scoop means, toward the upper portion of said beater means along a line of return impact forward of the topmost edge thereof.

5. The vehicular mixing machine of claim 4 wherein said impact deflector has a horizontally disposed bottom edge along which a selectively movable safety shield is hingeably attached.

6. The vehicular mixing machine of claim 5 wherein said safety shield is arcuately shaped, has a horizontally disposed bottom edge which contacts said flat surface when said impact deflector and said safety shield are both disposed substantially vertically, and is capable of being moved into closely spaced relationship with, and

in front of, said beater means, whereby said safety shield provides protection to operating personnel, rakes terminus material toward said beater means, and compresses said terminus material against the thrust of said scoop means.

7. The vehicular mixing machine of claim 2 wherein said rick intake means comprises:

- A. a pair of laterally spaced and outwardly diverging intake side sweepers, and
- B. a pair of inwardly bulging wheel wells.

8. The vehicular mixing machine of claim 7 wherein each of said pair of intake side sweepers is rigidly attached to one of said tunnel walls.

9. The vehicular mixing machine of claim 2 wherein said rick shaping means comprises:

- A. a pair of discharge side compressors, and
- B. a discharge top baffle having a bottom edge.

10. The vehicular mixing machine of claim 9 wherein said pair of discharge side compressors mutually converge upwardly and rearwardly.

11. The vehicular mixing machine of claim 10 wherein said pair of discharge side compressors comprises a pair of packing compressors, each packing compressor being rigidly attached to one of said tunnel walls, and a pair of shaping compressors, each shaping compressor being hingeably attached to said one of said packing compressors.

12. The vehicular mixing machine of claim 11 wherein a funnel compressor is hingeably attached to the inner surface of each packing compressor, is disposed to swing horizontally inwardly from said packing compressor, and has a vertically disposed trailing edge which is substantially parallel to the trailing edges of said packing compressor.

13. The vehicular mixing machine of claim 12 wherein each of said funnel compressors is hingeably mounted on a slide mounting whereby it is selectively alignable with the trailing edge of said adjacent funnel compressor.

14. The vehicular mixing machine of claim 13 wherein each of said funnel compressors is hydraulically operated and each of said shaping compressors is resiliently and hydraulically operated, whereby the pair of funnel compressors is able to compress the sides of an aerated rick as it is continuously and sequentially forming within said tunnel means.

15. The vehicular mixing machine of claim 11 wherein said beater means is a hammermill having a scoop means at the end of each hammermill arm.

16. The vehicular mixing machine of claim 15 wherein said scoop means is a paddle comprising a pair of angularly disposed blades, a concavity plate attached perpendicularly thereto and to said hammermill arm, and a deflecting plate attached to the leading edge of said concavity plate and inclined inwardly therefrom.

17. The vehicular mixing machine of claim 11 wherein said scavenger means comprises an arcuately shaped plow, having a forwardly disposed shave edge, which is disposed in said discharge portion transversely to said longitudinal axis and in annular relationship to said beater drum.

18. The vehicular mixing machine of claim 17 wherein said shave edge faces toward said front end, is disposed horizontally, and is aligned with the bottom edge of said tunnel walls.

19. The vehicular mixing machine of claim 18 wherein said plow is rigidly attached to each end to said packing compressors.

20. The vehicular mixing machine of claim 19 wherein said scavenger means further comprises a barrier guide which:

21. The vehicular mixing machine of claim 9 wherein said discharge top baffle is hingeably attached to said vehicle with a discharge hinge which is transversely disposed to said longitudinal axis.

22. The vehicular mixing machine of claim 21 wherein said discharge top baffle is adjustably movable along said discharge hinge with a discharge adjustment means which permits said bottom edge to contact the top surface of a rick of freshly aerated material, whereby the top thereof may be leveled.

23. The vehicular mixing machine of claim 1 wherein said beater means comprises a beater drum to the surface of which said scoop means are attached.

24. The vehicular mixing machine of claim 23 wherein said scoop means is a beater paddle which comprises a pair of intersecting and rigidly attached blades which are disposed mutually perpendicularly and in radial alignment with said beater drum.

25. The vehicular mixing machine of claim 24 wherein said pair of plates and the adjacent surface of said beater drum form a concavity therebetween which faces forwardly in the direction of rotation of said drum, whereby said concavity performs as a scoop during said rotation.

26. The vehicular mixing machine of claim 25 wherein said beater paddles are disposed in longitudinal rows spaced 60° apart along the periphery of said beater drum.

27. The vehicular mixing machine of claim 26 wherein said beater paddles of adjacent longitudinal rows are circumferentially disposed along approximately a 45° relationship to said longitudinal rows.

28. The vehicular mixing machine of claim 23 wherein said scoop means is a rounded scoop.

- A. is rigidly attached to said plow along the top edge thereof,
- B. is rigidly attached along the ends thereof to said packing compressors, and
- C. is disposed rearwardly toward the bottom edge

thereof.

29. The vehicular mixing machine of claim 2 wherein said straddle carrier vehicle further comprises:

- A. a pair of laterally spaced and vertically disposed front posts which are rotatably attached to said frame;
- B. a pair of laterally spaced and vertically disposed rear posts which are attached to said frame and are longitudinally spaced from said front posts;
- C. four wheels, each being rotatably attached at the bottom of one of said posts;
- D. a wheel drive means which is operatively connected to said power supply means; and
- E. a steering and control means.

30. The vehicular mixing machine of claim 29 wherein said machine is a vehicular composting machine which further comprises a hydrating means, comprising a front header and a rear header, each of said headers being disposed transversely of said longitudinal axis, above said beater means, and in straddling relationship to said beater means.

31. The vehicular composting machine of claim 30 wherein said headers are provided with a plurality of outlet nozzles which are selectively disposed to direct water forwardly, downwardly, and rearwardly.

32. The vehicular composting machine of claim 31 wherein said headers are connected to an extensible water supply means.

33. The vehicular composting machine of claim 30 wherein a plurality of vertically and longitudinally disposed separators are attached to said tunnel means in substantially equally spaced relation within said tunnel means.

34. The vehicular composting machine of claim 33 wherein a discharge baffle is hingeably attached to said tunnel means between each of said tunnel walls and said separators and between each of said separators, whereby a multi-rick is formed therewith having elongated, vertically disposed breathing slots which divide the rick into a plurality of flat-topped ricks.

35. The vehicular composting machine of claim 34 wherein each of said separators has a blunt leading edge and a gradually tapered trailing edge.

Column 10, line 45, delete "swpers" and insert --sweepers--.
Column 10, line 59, after "means", insert a comma (--,--).
Column 11, line 21, delete "disosed" and insert --disposed--.
Column 11, line 22, delete "approximatel" and insert --approximately--.
Column 11, line 45, delete "9and" and insert --and--.

UNITED STATES PATENT OFFICE
CERTIFICATE OF CORRECTION

Patent No. 3,776,528

Dated December 4, 1973

Inventor(s) Louis R. Toto

Page - 3

It is certified that error appears in the above-identified patent and that said Letters Patent are hereby corrected as shown below:

Column 11, line 57, delete "clump" and insert --clumps--.

Column 12, line 18, delete "965" and insert --95--.

Column 12, line 28, delete "perable" and insert --operable--.

Column 12, line 68, delete "hrough" and insert --through--.

Column 13, line 2, delete "read" and insert --rear--.

Column 13, line 26, insert --wall--between "tunnel" and "95".

Column 13, line 31, delete "packaging" and insert --packing--.

Column 13, line 45, delete "ompriss" and insert --compress--.

Column 13, line 55, delete "hat" and insert --that--.

Column 14, line 47, delete "no" and insert --not--.

Column 15, line 20, delete "hspital" and insert --hospital--.

Column 15, line 20, delete "practicalbe" and insert --practica-ble--.

Column 15, lines 27, 28, delete "largelykilled" and insert
--largely killed--.

Column 15, line 49, delete "periodica'ly" and insert --period-ically--.

Column 15, line 61, delete "blow" and insert --blew--.

UNITED STATES PATENT OFFICE
CERTIFICATE OF CORRECTION

Patent No. 3,776,528

Dated December 4, 1973

Inventor(s) Louis R. Toto

Page - 4

It is certified that error appears in the above-identified patent and that said Letters Patent are hereby corrected as shown below:

Column 16, line 18, delete "undercomposed" and insert --undecomposed--.

Column 16, line 49, delete "co" and insert --cob--.

Column 17, lines 9, 10, delete "threfrom" and insert --therefrom--.

Column 18, line 31, delete "eac" and insert --each--.

Column 18, line 37, delete "funnel" and insert --shaping--.

Column 19, line 4, delete "furthercomprises" and insert --further comprises--.

Column 19, line 5, presently beneath claim 28, sections "A, B and C" should be a part of claim 20.

In Figs. 2 and 3, "conc. warf" should be --concrete wharf--, as shown in the photocopy of the corrected first sheet of the drawings which were enclosed with the letter dated November 14, 1973 from the Chief Draftsman, in response to a 312 Amendment for this drawing correction which was filed on September 4, 1973 and "entered as directed to matters of form not affecting the scope of the invention (0.3311)" by the Examiner's Letter dated November 14, 1973.

Signed and sealed this 15th day of October 1974.
